US00D991402S

(12) **United States Design Patent** (10) Patent No.: **US D991,402 S**
(45) Date of Patent: **** Jul. 4, 2023**

(54) **AERATOR INSERT FOR TAPS**

(71) Applicant: **Xiamen Water Nymph Sanitary Technology Co., Ltd.**, Fujian (CN)

(72) Inventors: **Huaqiang Zhou**, Fujian (CN); **Weihai Mu**, Fujian (CN)

(**) Term: **15 Years**

(21) Appl. No.: **35/515,159**

(22) Filed: **Jul. 25, 2022**

(80) **Hague Agreement Data**

Int. Filing Date: **Jul. 25, 2022**

Int. Reg. No.: **DM/223209**

Int. Reg. Date: **Jul. 25, 2022**

Int. Reg. Pub. Date: **Sep. 16, 2022**

(30) **Foreign Application Priority Data**

Jan. 25, 2022 (CN) 202230051997.9

(51) **LOC (14) Cl.** **23-01**

(57) **CLAIM**

The ornamental design for aerator insert for taps, as shown and described.

DESCRIPTION

1. Aerator insert for taps

1.1 : Perspective

1.2 : Perspective

1.3 : Front

1.4 : Top

1.5 : Bottom

1.6 : Left

1.7 : Reference view

Fig. 1.1 is a perspective view of the aerator insert for taps; fig. 1.2 is another perspective view thereof; fig. 1.3 is a front view thereof, the rear view being identical and having been omitted; fig. 1.4 is a top view thereof; fig. 1.5 is a bottom view thereof; fig. 1.6 is a left view thereof, the right view being identical and having been omitted; fig. 1.7 is reference view showing the state in use and form no part of the claimed design; the broken lines in the drawings depict portions that form no part of the claimed design.

1 Claim, 7 Drawing Sheets
